UNITED STATES PATENT OFFICE.

RALPH G. JACKSON, OF CHESTER, PENNSYLVANIA, ASSIGNOR TO THE CONGOLEUM COMPANY, OF PHILADELPHIA, PENNSYLVANIA, A CORPORATION OF PENNSYLVANIA.

FLOOR-COVERING.

1,255,095.

Specification of Letters Patent.

Patented Jan. 29, 1918.

Application filed August 6, 1917. Serial No. 184,669.

To all whom it may concern:

Be it known that I, RALPH G. JACKSON, a citizen of the United States, and a resident of Chester, county of Delaware, State 5 of Pennsylvania, have invented certain Improvements in Floor-Coverings, of which the following is a specification.

My invention relates to certain improvements in floor coverings of the oil cloth or 10 linoleum type, in which the base consists of felted material.

The object of the invention is to prevent the material from tearing when excessive strains are placed upon it during the handling of the goods, or while the material is 15 on the floor.

The invention is particularly adapted for use in connection with rugs made of this material which have a base of felt, although 20 it will be understood that it can be used in connection with strip material as well.

In the accompanying drawings:

Figure 1 is a plan view showing a rug, with a portion of the felt exposed, showing 25 the reinforcing stitching;

Fig. 2 is a sectional perspective view, showing the felt after stitching and before the paint is applied;

Fig. 3 is a perspective view of the rug, 30 showing the paint wearing surface applied;

Fig. 4 is a plan view illustrating a rug in which the reinforcing stitching extends across the entire body of the rug; and

Fig. 5 is a view of a base made in two 35 plies stitched together.

Referring to the drawings, 1 is a rug of any suitable size. This rug has a felt base 2 and a paint wearing surface 3, of any suitable thickness, and there is usually a 40 paint cover surface 4 at the bottom so as to lend finish to the rug and to prevent it from adhering to the floor. The rug has usually an ornamental center 5, shown in Fig. 1, and a border 6, of any suitable design, to harmonize with the center.

Rugs of this type have been manufactured, but unless considerable care is exer-

cised they are liable to be torn when handled by inexperienced persons, due to the fact that the base is made of felt produced 50 from cotton, or other suitable material, and certain kinds of felt will tear when subjected to excessive strains. This is particularly true in rugs of large sizes, which are now being made. To overcome this difficulty, I form a row of stitches x , preferably at each side of the rug near the edge, and also a row of stitches x' at or near each end of the rug, and, in some instances, these stitches are supplemented by a second row 55 of stitches x^2 at the inner edge of the border, both at the side and at the end, as shown in Fig. 1. These stitches prevent the tearing of the felt when strains are placed upon it and also add considerably to the durability of the rug as a whole.

The stitches are formed before the paint covering is applied and when the rugs are made in long strips the end stitches x' and x^2 are so distributed that they will come at 70 the proper places when the rug is printed. In some instances, the stitches may extend across the entire surface of the rug, where additional reinforcement is required, and these stitches may be formed as illustrated 75 at x^3 , Fig. 4, or in any other manner desired so as to strengthen materially the felt base. The stitching is completed prior to the saturation of the rug with a semi-solid bituminous compound so that the compound 80 will fill the holes made by the stitching and when the paint is applied to the surface the stitches are covered so as to be imperceptible, the appearance of the rug being the same as that of an ordinary rug.

Where the rug is made in two or more plies of felt, as in Fig. 5, the stitching may be used not only as a means of preventing the tearing of the rug, but also as a means for holding the plies together, in addition 90 to the ordinary felting of the plies.

I claim:

1. A floor covering having a felt base and a painted wearing surface; and a series of

reinforcing stitches extending through the base for preventing tearing of the felt, the painted wearing surface covering the stitches on the surface of the material.

5 2. A floor covering having a saturated felt base and having a painted wearing surface; and a series of reinforcing stitches formed

near the edge of the base so as to prevent tearing of the same, the openings in the felt formed by the stitches being closed by the saturating material, the painted wearing surface concealing the stitches.

In witness whereof I affix my signature.
RALPH G. JACKSON.
